(57) **CLAIM**

The ornamental design for a laser processing machine, as shown and described.

DESCRIPTION

FIG. 1 is a perspective view of a laser processing machine showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged top, front, perspective detailed view of the working head part of the laser processing machine as shown in circle 8-9 in FIG. 2; and,

FIG. 9 is an enlarged bottom, front, perspective detailed view of the working head part of the laser processing machine as shown in circle 8-9 in FIG. 2.

The broken lines are shown for illustrative purposes only and form no part of the claimed design. The dot-dashed lines denote the boundary of the claim, and form no part of the claimed design.
